TABLE OR THE LIKE

Alfred C. Hoven, William S. Lindberg, and Walter E. Nordmark, Grand Rapids, Mich., assignors to American Seating Company, Grand Rapids, Mich., a corporation of New Jersey

Application October 24, 1956, Serial No. 43,505

Term of patent 14 years

(Cl. D33—14)

Fig. 1

Fig. 2

Des. 180,283

PAGE 2

*Fig. 4Fig. 5*Figure 1 is a perspective view of a table or the like, showing our new design;

We claim:

The ornamental design for a table or the like, substantially as shown.
